UNITED STATES PATENT OFFICE.

LYNN A. VIETOR, OF EUREKA, CALIFORNIA.

DESIGN FOR A STREET LAMP.

Application filed December 15, 1923. Serial No. 8,061. Term of patent 3½ years.

To all whom it may concern:

Be it known that I, LYNN A. VIETOR, a citizen of the United States, residing at Eureka, in the county of Humboldt and State of California, have invented a new, original, and ornamental Design for a Street Lamp, of which the following is a specification, reference being had to the accompanying drawing, forming part thereof.

Figure 1 is an elevation of a street lamp showing my new design.

Fig. 2 is an enlarged transverse section on line 2—2, Fig. 1.

I claim:

The ornamental design for a street lamp, as shown.

LYNN A. VIETOR.
